UNITED STATES PATENT OFFICE.

NICHOLAS A. PETRY, OF PHILADELPHIA, PENNSYLVANIA.

MUFFLER CUT-OUT FOR MOTOR-CARS.

1,215,185.

Specification of Letters Patent.

Patented Feb. 6, 1917.

Application filed March 10, 1916. Serial No. 83,255.

To all whom it may concern:

Be it known that I, NICHOLAS A. PETRY, a citizen of the United States, residing in Philadelphia, Pennsylvania, have invented 5 certain Improvements in Muffler Cut-Outs for Motor-Cars, of which the following is a specification.

My invention relates to that class of muffler cut-outs in which a casing interposed in 10 the exhaust pipe is provided with a valve adjustable to cut off the flow of gases to the muffler and direct them through an outlet in the casing, or so as to close said outlet and permit the gases to flow through the casing to the muffler, the object of my invention being to simplify and cheapen the construction and to improve the operation of a muffler cut-out of this type.

In the accompanying drawings—

20 Figure 1 is a longitudinal section of a muffler cut-out constructed in accordance with my invention;

25 Fig. 2 is a perspective view of one half of the same, and of the valve removed therefrom;

Fig. 3 is a horizontal section on the line 3—3, Fig. 1;

Fig. 4 is a transverse section on the line 4—4, Fig. 1;

30 Fig. 5 is a transverse section on the line 5—5, Fig. 1;

Fig. 6 is a side elevation of one half of a special form of casing, the valve used in connection therewith being shown in section;

35 Fig. 7 is a transverse section of the complete casing on the line 7—7, Fig. 6, and

Fig. 8 is a view similar to Fig. 3, but illustrating still another type of casing.

40 The muffler cut-out constructed in accordance with my invention consists of a casing fitted at its opposite ends to the adjoining portions 11—11^a of the exhaust pipe of the engine, through which the exhaust gases 45 travel, in the direction of the arrow α Fig. 1, from the engine to the muffler mounted on the portion 11^a of the exhaust pipe.

The interposed casing comprises a central member 12 of rectangular cross section 50 with longitudinally curved top and opposite end members 13 and 13^a of circular cross section for being fitted to the opposite members 11—11^a of the exhaust pipe, the central portion 12 of the casing containing a 55 chamber 12^a having at the bottom a down-

wardly and rearwardly discharging funnel 12^b.

When the casing is composed of cast metal, it preferably consists of opposite halves meeting on the central longitudinal line of 60 the casing, so that they can be cast without the use of cores, the two halves of the casing being secured together and to the pipe sections in any suitable manner, as for instance by providing them with lugs 14 for 65 the reception of clamping bolts.

Extending transversely across and projecting upwardly at an angle into the chamber 12^a of the casing is a partition 15 having, at its inner end, a segmental rib 16 70 with transverse opening extending through the same for the reception of the hub member 17 of a valve plate 18 which, when so mounted in said rib, (and preferably also in bearings in the side plates of the casing) 75 can be swung either upwardly to the position shown by full lines in Fig. 1, or downwardly to the position shown by dotted lines therein.

When the valve is in the position shown 80 by full lines it directs the exhaust gases from the pipe 11 downwardly through the chamber 12^a below the partition 15 and out through the funnel 12^b in the lower portion of the casing, and when said valve is in the 85 position shown by dotted lines it directs the exhaust gases upwardly through the chamber 12^a over the top of the partition 15 and into the muffler pipe 11^a, the valve when in either position deflecting the gases without 90 any abrupt change in the direction of flow and therefore without any material resistance to such flow.

The deflector for the gases therefore combines a permanent member (the inclined 95 partition 15) and an adjustable member (the valve 18) the member 15 acting constantly, and the member 18 determining whether such deflection shall be over or under the permanent member 15.

The inclined partition 15 is preferably formed in one piece, integral with one side of the central member 12 of the casing, as shown in Fig. 2, so as to dispense with any central joint in said partition, although it can, without departing from the essential features of my invention, be composed of halves each carried by its respective half of the casing and meeting midway of the chamber 12^a.

110

A muffler cut-out constructed in accordance with my invention is composed of but few parts which can be fitted together without expensive machining and each of these parts can be cheaply produced. A still cheaper method of production can, as shown in Figs. 6 and 7, be adopted by making the opposite halves of the casing of pressed steel or other sheet metal, the central partition 15 in such case being separate from the sides of the casing and being secured thereto by means of a flange formation 19 at either or both edges of said partition, which flange can be secured to the respective side of the 15 casing by electric welding or other simple means, the same means being employed for securing in place a flange 20 which constitutes a seat for the valve 18 when the latter is in position to close the cut-out passage.

20 In order to facilitate the formation of the hollow segmental rib at the top edge of the partition when this method of manufacture is adopted, said partition is preferably composed of two plates 15^a and 15^b welded or 25 otherwise secured together and each having at its upper edge a curved flange 16^a or 16^b constituting, respectively, the upper or lower member of said segmental rib.

When the opposite halves of the casing 30 are composed of pressed metal, as described, the two halves may be connected in any suitable way, as for instance by crimping together edge flanges on the opposite halves of the casing, as shown in Fig. 7.

35 Another method of forming the casing of the cut-out within the scope of my invention is to cast the same in one piece, as shown in Fig. 8, but, in such case, cores have to be employed in the mold and an 40 opening 21 will have to be formed at one side of the casing for the insertion of the valve 18 and its hub 17, such opening being subsequently closed by a plate 22.

Preferably also, in this case, a similar 45 opening with detachable closure is provided at the opposite side of the casing in order to permit ready machining of the valve seats, if the same is required.

When sufficient bearing is provided in the 50 opposite sides of the casing 12 for the pivot hub 17 of the swinging valve the segmental rib at the inner end of the partition 15 may in some cases be omitted, such pivot hub bearing against the inner end of the partition to form a reasonably tight joint therewith.

The projecting end of the pivot hub of the valve is intended to be provided with an operating arm or lever whereby it can be 60 readily swung to one position or the other, and such lever is preferably acted upon by a suitable spring tending to move the valve 18 into position to close the cut-out passage.

The curved top 12 of the casing is 65 concentric with the casing of the seat for the

valve stem at the inner end of the partition 15, hence the area of the passage 12^a above the partition is, in all of its parts, equal to the area of the valve seat at the forward end of the passage.

The hollow segmental rib 16 at the inner end of the partition 15 is in excess of a semi-circle so as to overlap the segmental rib 17 on the valve and thus prevent radial removal of the valve from its seat in any position of adjustment of said valve.

When, as in a muffler cut-out, members for attachment to the muffler pipe are at opposite ends of the casing and the cut-out branch projects at an angle from the connecting member the use of the inclined inwardly projecting partition 15 permits of the formation of a portion of the cut-out passage within said connecting member, and thus reduces the size of the latter and also its weight, as compared with that of one having a cut-out passage wholly beyond the bottom of the connecting member, while at the same time the use of the inwardly inclined projecting partition reduces the radial projection of the valve beyond its seat to such an extent that it is less than the diameter of the end members.

I claim:

1. A muffler cut-out comprising a casing 95 having a central member with longitudinally projecting end members for application to the muffler pipe, and a cut-out branch projecting from said central member at an angle to the pipe receiving members, said central member also having an inwardly projecting transverse partition disposed at an angle to the axial line of the end members, and a swinging valve pivoted at the inner end of said partition and adjustable to a position to close the through passage or to a position to close the cut-out branch, the latter being formed partly within the central member of the casing.

2. A muffler cut-out comprising a casing 110 having a central member with longitudinally curved top and straight sides, longitudinally projecting end members for application to the muffler pipe, and a cut-out branch projecting from said central member at an angle to the pipe receiving members, said central member also having an inwardly projecting inclined transverse partition, and a swinging valve pivotally mounted at the inner end thereof, and free 115 to assume a position substantially in line with the partition for closing the longitudinal passage through said central member or a position substantially at a right angle to the inclined partition for closing the entrance to the cut-out branch.

3. A muffler cut-out having a casing comprising a central member with longitudinally projecting end members for application to the muffler pipe, a cut-out branch 120

projecting from said central member at an angle to the pipe receiving members, an inwardly projecting inclined transverse partition and a valve pivotally mounted at the 5 inner end of the latter and adjustable in respect thereto so as either to close the muffler pipe and open the cut-out branch or close the cut-out branch and open the muffler pipe, said casing being composed of laterally separable members and said inclined transverse 10 partition extending across the casing from side to side and being formed integrally with one of said laterally separable members.

4. A muffler cut-out comprising a casing 15 having a central member with longitudinally projecting end members for application to the muffler pipe, and a cut-out branch projecting at an angle to said end members, said central member also having an in-

wardly projecting transverse partition disposed at an angle to the axial line of the end members, and a swinging valve pivoted at the inner end of said partition and adjustable in respect thereto so as either to close the muffler pipe and open the cut-out 20 branch or close the cut-out branch and open the muffler pipe, that portion of the valve which projects beyond its seat on the partition being narrower radially than the diameter of the pipe receiving members. 25

In testimony whereof I have signed my name to this specification in the presence of two subscribing witnesses.

NICHOLAS A. PETRY.
